(57) **CLAIM**

The ornamental design for a hub for routing security sensor data, as shown and described.

DESCRIPTION

FIG. 1 is a bottom plan view of a hub for routing security sensor data, showing our new design;

FIG. 2 is a front view thereof;

FIG. 3 is a first side front perspective view thereof;

FIG. 4 is a first side view thereof;

FIG. 5 is a first side rear perspective view thereof;

FIG. 6 is a rear view thereof;

FIG. 7 is a second side rear perspective view thereof;

FIG. 8 is a second side view thereof;

FIG. 9 is a second side front perspective view thereof; and,

FIG. 10 is a top plan view thereof.

The broken lines immediately adjacent the claim represent the bounds of the claimed design while all other broken lines are directed to environment and are for illustrative purposes only; the broken lines form no part of the claimed design.
